UNITED STATES PATENT OFFICE.

JOHN KONSEL, OF NEW YORK, N. Y., ASSIGNOR OF ONE-FOURTH TO JOSEPH HAVRANEK,
OF NEW YORK, N. Y.

AUTOMATIC TRAIN CONTROL.

1,168,010.

Specification of Letters Patent.

Patented Jan. 11, 1916.

Application filed May 1, 1915. Serial No. 25,229.

To all whom it may concern:

Be it known that I, JOHN KONSEL, a subject of the Emperor of Austria-Hungary, residing at New York, in the county of New York and State of New York, have invented new and useful Improvements in Automatic Train Controls, of which the following is a specification.

This invention relates to automatic train controls and it consists in the novel features hereinafter described and claimed.

An object of the invention is to provide an electrically operated train control of simple structure, the parts of which may be arranged along the track of a road in a manner to be acted upon by the wheel flanges of a passing train to position certain members adapted to coöperate with devices carried by all trains which use the same track whereby a second train is prevented from entering a block upon which the first train may be standing or traveling. The parts of the device are so arranged that when the first train to enter a block leaves the same the parts at the entrance end of the block are caused to assume normal positions, out of the way, so that a following train may readily enter the said block without the interruption on the part of the controlling apparatus.

In the accompanying drawings:—Figure 1 is a diagrammatic view of the train control. Fig. 2 is a top plan view of features of the same. Fig. 3 is a side elevation with parts in section of the device which is positioned in the vicinity of the entrance end of the block of the track. Fig. 4 is a similar view of a feature adapted to be engaged by the wheel flanges of a train passing over the block. Fig. 5 is a similar view of a feature located in the vicinity of the exit end of the block.

As illustrated in the accompanying drawings the device is shown in conjunction with a track rail 1 which at suitable intervals along its length is divided into blocks in the usual manner. A current wire 2 and a return wire 3 extend along the rail 1 and are connected with any suitable source of electric supply (not shown). A frame 4 is located adjacent the rail 1 in the vicinity of the entrance end of the block thereof and a coil 5 is mounted upon the said frame. A wire 6 electrically connects a coil 5 with the current wire 2. A core 7 is movably mounted

in the coil 5 and is provided at one end with a head 8. A spring 9 is interposed between the head 8 and the adjacent end of the frame 4 and is under tension with a tendency to normally maintain the head 8 in a position remote from the said frame. That end of the core 7 opposite the end thereof which carries the head 8 is beveled as at 10 and a lug 11 is provided upon the frame 4 and is located in the path of movement of the bevel end of the core 7 and is adapted to limit the sliding movement of the said core with relation to the frame 4. A triangular block 12 is pivotally mounted in the frame 4 adjacent the beveled end 10 of the core 7 and is provided with journaled rollers 13 and 14.

When the coil 5 is not energized the spring 9 holds the core 7 in the position shown in Figs. 1 and 2 of the drawings and the beveled end 10 of the said core is held from under the block 12 so that the block lies down in the frame 4 as best shown in Fig. 1 of the drawing and below the upper surface of the track rail 1. When the coil 5 is energized by electric current passing therethrough (as will be hereinafter explained) the core 7 is moved longitudinally therein and assumes the position shown in Fig. 3 of the drawings. The longitudinal movement of the said core compresses the spring 9 between the head 8 and the adjacent end of the frame 1 and the beveled end portion of the core 7 passes under the block 12 and the roller 14 rides up along the beveled end 10 of the said core and the block 12 assumes the position shown in Fig. 3. When in this position it will be observed that the roller 13 is supported above the upper surface of the track rail 1 and the beveled end of the core 7 is in contact with the adjacent side of the lug 11. Consequently it will be seen that the lug 11 limits the longitudinal movement of the core 7 in the frame 4 and the coil 5.

A frame 15 is positioned adjacent the track rail 1 and a coil 16 is mounted upon the said frame 15. A core 17 is mounted for vertical movement in the coil 16 and carries at its upper end a plate 18. A spring 19 is interposed between the under side of the plate 18 and the adjacent side of the frame 15 and is under tension with a tendency to hold the said plate in a position remote from the frame 15. A cup 20 is mounted upon the frame 15 and carries in its lower

portion a volume of liquid electric conducting substance 21 which may be of mercury or its equivalent. A volume of oil 22 is located in the upper portion of the cup 20 and rests upon the upper surface of the mercury 21. Spaced pins 23 and 24 are carried by the plate 18 and pass down through the top of the cup 20. The pins 23 and 24 are normally maintained in an elevated position as shown in Fig. 4 of the drawings under the tension of the spring 19 which is interposed between the frame 15 and the plate 18. Consequently it will be seen that the lower ends of the pins 23 and 24 are normally held in the oil 22 and out of contact with the mercury 21. A curved arm 25 is pivotally mounted adjacent the frame 15 and the free end of the said arm rests upon the upper surface of the plate 18 in the vicinity of the center of the upper end of the core 17. A wire 26 is connected at one end with the coil 5 and at its other end with the pin 23. A wire 27 is connected at one end with the pin 24 and at its other end with the coil 16. The arm 25 is located adjacent the inner side of the track rail 1 and the free end portion of the said arm is normally held in the vicinity of the upper surface of the track rail or slightly above the upper surface of the same as shown in Figs. 1 and 4 of the drawings.

A frame 28 is located adjacent the side of the track rail 1 but in the vicinity of the exit end of the next adjacent block at which the frames 4 and 15 are located. A coil 29 is mounted upon the frame 28 and a core 30 is movably mounted in the said coil. A stop 31 is mounted upon the core 30 and a spring 32 is interposed between the frame 28 and the said stop and is under tension with a tendency to hold the said stop at a position remote from the coil 29. The core 30 is provided with a rounded end 33 which is adjacent the stop 31. A bolt 34 is slidably mounted in the frame 28 beyond the rounded end 33 of the core 30 and carries at its upper end a plate 35. A spring 36 is interposed between the plate 35 and the adjacent side of the plate 28 and is under tension with a tendency to hold the plate 35 at a position remote from the said frame. A stop 37 is mounted upon the bolt 34 at a point between the upper and lower sides of the frame 28 and the upper end of the said stop normally engages under the rounded end 33 of the core 30 as best shown in Fig. 5 of the drawing. A stop 37 is approximately conical in configuration with its larger end uppermost. An arm 38 is pivotally mounted upon the frame 28 and the free end of the said arm rests upon the upper surface of the plate 35. The arm 38 is provided at its pivoted end with angularly disposed extensions 39 as best shown in Fig. 5 of the drawings. Cups 40 and 41 are mounted upon the frame 28

and are provided in their lower portion with quantities of quicksilver, or similar material, indicated at 42. The upper portions of the cups 40 and 41 contain volumes of oil indicated at 43. Pins 44 are pivotally connected with the extensions 39 and pass down through the tops of the cups 40 and 41. An electric wire 45 connects the pins 44 together. A wire 46 connects one of the pins 44 with the coil 16 mounted upon the frame 15. A wire 47 passes through the sides of the cups 40 and 41 and electrically connects the volumes of mercury 42 in the said cups together. A wire 48 electrically connects the mercury 42 in the cup 40 with the coil 29 and a wire 49 electrically connects the coil 29 with the return wire 3. A tappet 50 (see Fig. 1) is adapted to be carried by the engine or car which passes over the track rail 1 and the said tappet may be operatively connected in any appropriate manner, with the throttle valve of the engine or the brake valve of the air system for controlling the movement of the engine when the tappet encounters the roller 13 when the block 12 is extended above the upper surface of the track rail 1.

The operation of the train control is as follows:—Assuming that the parts are in the positions as shown in Fig. 1 of the drawings, and an engine or train is moving along the track rail 1 in the direction indicated by the arrow in the said figure. The flange of one of the wheels, (not shown) strikes the arm 25 and depresses the same whereby the plate 18 and pins 23 and 24 are moved in a downward direction and the lower end portions of the said pins 23 and 24 enter the mercury or quicksilver 21. At the same time the core 17 is moved in a downward direction against the tension of the spring 19 and is located well within the coil 16. Current then flows from the wire 2 along the wire 6 and through the coil 5 energizing the same and thus the core 7 is moved longitudinally through the coil 5 against the tension of the spring 9. When the beveled end 10 of the core 7 encounters the roller 14 the block 12 is swung from a lower position as shown in Fig. 1 to an elevated position as shown in Fig. 3 and is held temporarily at the said elevated position. When in the elevated position described the roller 13 is supported above the upper surface of the track rail 1. From the coil 5 the current passes along wire 26 to pin 23 thence through the quicksilver 21 to pin 24 thence from the pin 24 along wire 27 to the coil 16. Therefore the coil 16 is energized and the core 7 is held in a lower position therein against the tension of the spring 19. From the coil 16 the current passes along the wire 46 and thence through the wire 45 and through the pin 44 which enters the cup 41 to the quicksilver 42 in the said cup 41. The current then passes along

the wire 47 to the quicksilver in the cup 40 thence along wire 48 through the coil 49 which is energized. The current then passes from the coil 29 along the wire 49 to the return wire 3.

When the coil 29 becomes energized the core 30 is moved longitudinally in the said coil against the tension of the spring 32 and the rounded end 33 of the said core is withdrawn from over the upper larger end of the stop 37 upon the bolt 34. Thus the said bolt 34 is locked in its lowest position. When the electric circuit is interrupted as just above described the magnetic core 16 is deenergized whereby the tension of the spring 19 comes into play and the core 17 and plate 18 are moved in an upward direction and the said parts together with the arm 25 assume the positions as shown in Fig. 4 of the drawings which are the normal position of these features of the invention. When the pins 23 and 24 are moved up out of contact with the quicksilver 21 in the cup 20 the electric circuit above described is again broken at this point and consequently the magnetic coil 5 is deenergized and the core 7 is moved under the tension of the spring 9 so that its beveled end portion is carried from under the block 12 and the said block 12 by gravity swings down into its normal position in the frame 4, the same as indicated in Fig. 1 of the drawings.

From the above description taken in conjunction with the accompanying drawings it will be seen that a train control device of simple and durable structure is provided and that the parts positively coöperate with each other in a manner to efficiently control the movement of a succeeding train over the track way and that the operating action is automatic throughout the system.

Having described the invention what is claimed is:

1. In a train control a track, an arm movably mounted with relation to the track and adapted to be engaged by the flange of a wheel passing along the track, a magnet located adjacent the arm, a spring supported core movably mounted in the magnet and adapted to be depressed by the arm, an open circuit connected with the magnet and means carried by the core for closing the circuit and operable to close the circuit when the said core is depressed. 105
2. In a train control a track, an arm pivotally mounted adjacent the track and adapted to be depressed by the flange of a wheel passing along the track, a magnet located adjacent the arm, a spring supported core movably mounted in the magnet and movable by the arm when the arm is depressed, spaced pins movably mounted with the core, a cup receiving said pins, a circuit connected with the pins and the magnet and a liquid electric conductor located in the cup and in which the pins are adapted to be immersed when the core is depressed. 110
3. In a train control a track, an arm pivotally mounted adjacent the track, a spring supported bolt against which the free 125

41
end of the arm bears, a stop mounted upon the bolt, a magnet located adjacent the bolt, a core movably mounted in the magnet and engageable with the stop, a circuit connected with the magnet and means carried by the arm for breaking the circuit.

4. In a train control a track, an arm pivotally mounted adjacent the track and having extensions, a spring supported bolt 19 for supporting the arm, a stop carried by the bolt, cups located adjacent the arm, pins carried by the extensions of the arm and entering the cups, means electrically connecting the pins together, electric transmitting fluid

located in the cups and adapted to be entered successively by the pins, the said pins at an interval being out of engagement with both bodies of fluid, means electrically connecting the bodies of fluid together and means electrically connecting one of the 20 bodies of fluid with the magnet.

In testimony whereof I affix my signature in presence of two witnesses.

JOHN KONSEL.
